(57) **CLAIM**

The ornamental design for cartridge for fluid emitting device, as shown and described.

DESCRIPTION

FIG. 1 is a front, left side, top perspective view of a cartridge for fluid emitting device showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference perspective view thereof, showing a state in which this article is used.

In the drawings, the broken lines depict environmental structure that form no part of the claimed design.

1 Claim, 4 Drawing Sheets
